(57) **CLAIM**

The ornamental design for the non-contact voltage tester, as shown and described.

DESCRIPTION

FIG. 1 is a perspective view of the non-contact voltage tester.

FIG. 2 is a right side view of the non-contact voltage tester.

FIG. 3 is a left side view of the non-contact voltage tester.

FIG. 4 is a top view of the non-contact voltage tester.

FIG. 5 is a bottom view of the non-contact voltage tester.

FIG. 6 is a front view of the non-contact voltage tester; and,

FIG. 7 is a rear view of the non-contact voltage tester.
